BARRETT COMPANY, OF NEW YORK, N. Y., A CORPORATION OF NEW JERSEY

PROCESS OF DISTILLING TAR

Application filed October 15, 1927. Serial No. 226,324.

This invention relates to improvements in the distillation of tar, and particularly to the utilization of the heat available in the gases produced in coal-carbonization plants to distill tar and to produce oils and pitches by such distillation. The invention will be described especially with reference to its application to coke ovens.

In the ordinary operation of by-product coke ovens the gases produced by the coking operation pass from the individual ovens through uptake pipes and goose necks to a collector main common to the ovens of the battery. The gases, commonly known as "foul" gases, leave the ovens at high temperature, e. g., 600° to 700° C. or higher, and carry a considerable proportion of volatilized tars and oils. Ordinarily the gases are cooled as rapidly as possible by the application of sprays of ammonia liquor or ammonia liquor and tar in the goose-necks and collector main, the heat in the gases being thereby dissipated and lost. The rapid cooling causes separation of tar containing heavier oils in the collector main. Further cooling is effected in the cross-over main which connects the collector main to the condensing system and an additional quantity of tar or tarry oil carrying both heavier and lighter oils is thus separated. The collected tar is commonly shipped from the coke-oven plant to a tar-distillation plant for distillation and separation of the oils and the production of pitches of varying qualities. Handling losses, freight charges and distillation costs, including fuel and capital and maintenance expenses for the special equipment required for distillation, add to the cost of production of the tar-distillation products.

It is an object of the present invention to provide a method and apparatus which permit the distillation of tar at a coal-distillation plant, such as a coke-oven plant, the utilization of the heat of the coal distillation gases for that purpose, and particularly the enrichment of the gases in oil vapors and the production of clean oils directly by such distillation, together with pitches having the

various qualities and characteristics required by the trade.

A further object of the invention is the utilization of the hot coal distillation gases to distill the tar in successive operations followed by electrical precipitation of the gases so utilized. This permits the production of heavier pitches and the recovery of distinct oil condensates, that is to say, a light oil from the first distillation and heavier oils from the successive distillations. Several desirable products are obtained thus in a single and continuous distillation of the tar by utilizing the hot gases as they are discharged from the ovens of the battery.

According to the present invention the heat of the coke-oven or other coal distillation gases as they come from the coke ovens or retorts is utilized to distill tar and to separate volatile oils therefrom by spraying or otherwise bringing the tar into intimate contact with the hot gases, and the resulting gases carrying the vapors and the particles of tar and "tar fog" are subjected immediately to electrical precipitation to remove the liquid and solid constituents from the gases, leaving therein the vapors of condensable oils which, upon subsequent cooling of the gases, yield clean oils.

To effect the desired distillation the tar or other material to be distilled is brought into intimate contact with the gases at the bottom of the electrical precipitator so that the fine particles of tar are subjected immediately to the distilling effect of the hot gases and the resulting gases are then immediately passed through the electrical precipitator. The gases are somewhat cooled by the absorption of heat both as sensible heat and as latent heat of vaporization of the tar or other material. The distillation and separation of the vaporizable oils is thus accomplished immediately. The operation has, moreover, a beneficial effect upon the electrical precipitator operation inasmuch as the gases passing therethrough are loaded with finely divided particles of tar or "tar fog" which, being separated upon the walls of the precipitator tubes, flow downwardly and flush the tube walls tending thereby to pre-

80

85

90

95

100

vent any accumulation of tar or pitch, thereby maintaining the precipitator in a condition for continuous operation. The tar and pitch particles which are agglomerated in the electrical precipitator and which flow backwardly into the lower part thereof are again subjected to heating by the hot gases and to further distillation effect thereby. The liquid thus subjected to the repeated heating effect of the gases with resultant loss of volatile constituents collects in the bottom of the electrical precipitator in the form of pitch and may be withdrawn and utilized as such while the gases, which escape from the top of the precipitator after being freed from solid and liquid particles, may be cooled to condense and recover clean oils therefrom.

It will be understood by those skilled in the art that the coke oven gases arising from the ovens contain vapors of condensable coal tar oils and contain also, as entrained material, coal and coke dust and non-volatile pitch or tarry constituents commonly known as tar fog. At high gas temperatures, the tar fog is present as high melting point pitch. At lower temperatures, the melting point of this pitch is lower, due to condensation from the gases of heavier oils which blend with the pitch and lower its melting point. At temperatures applying in the ordinary collector main and in cross-over mains and condensers, such large quantities of oils have been condensed that the tar fog is present as ordinary tar.

It will be understood, therefore, that the pitch finally resulting from the process of my invention is made up partly of the residue of distillation of the tar added and partly of the pitch normally occurring in the hot coke oven gases.

Likewise, the clean oils recovered from the gases cleaned by the electrical precipitator are made up partly of oils resulting from distillation of the added tar and partly of the oils normally occurring as vapors in the hot coke oven gases.

The dew points of the gases for the several constituents carried therein as vapor are lower than the normal boiling points of these constituents and by suitable regulation of the temperature of the gases during distillation, for example, by variation of the rate at which tar is introduced, it is possible to retain the desired oils therein as vapors while the heavy tarry constituents are precipitated. Thus, by controlling the temperature of the gases either before or during the distillation all or substantially all of the tarry constituents of the tar to be distilled can be retained in the liquid phase while the desired oils are vaporized and carried away with the gases. The temperature of the exit gases should, to accomplish the intended purpose, be maintained above the dew point of

the gases for the most readily condensable oil constituents desired so that substantially all of the desired oils will be retained in the gases as vapors while the tarry or pitch constituents remain as liquid, part of which settles out of the gas and part of which is separated from the gases in the electrical precipitator and is blended with the pitch at the bottom of the precipitator.

The cooling of the gases, when the gases are to be employed below their maximum temperature, can be effected not only by modifying the amount of tar introduced to the stream of gases but also by employing other cooling agents such as oil or ammonia liquor, either or both of which may be sprayed with the tar into the bottom of the electrical precipitator or introduced to the gases before they enter the precipitator. Or the oil or ammonia liquor or other aqueous cooling agent can be mixed with the tar before the latter is brought intimately in contact with the hot gases. By thus cooling the gases to the desired degree the temperature of distillation and of subsequent separation of the tar and pitch constituents from the gases can be regulated and controlled to ensure the production of pitches having the desired consistency and the recovery of the required proportion of oils of desired composition from the tar; while by avoiding such cooling, and by employing the gases at a high temperature, effective distillation can be obtained with a smaller amount of gases, and high melting point pitches and high oil yields readily obtained.

The heat available in the gases from a coke-oven battery is from twenty-five to forty times the amount required for the distillation of all of the tar produced by the battery to soft or medium pitch. Consequently if all of the heat available in the hot gases is utilized it will be necessary either to add water or ammonia liquor in regulated amounts to the gases or to supply tar or oil from other sources; as an alternative the tar from the battery can be accumulated and distilled at intervals by the operation as described. If only tar from a single battery is to be distilled it will be sufficient usually to provide one or more precipitators which may be supplied with hot gases from one or more of the ovens of the battery.

The invention presents the advantage, among others, that it enables the hot coke oven or other coal distillation gases to be employed for distillation at a temperature approaching their maximum temperature, thus enabling rapid distillation to be obtained, high melting point pitches to be readily produced, and large increase in vapors, particularly vapors of heavy or high boiling oils to be obtained in the escaping gases.

In carrying out the invention no substan-

tial modification of the usual coke-oven battery and recovery system is required, that is to say, the ovens may be connected through the usual uptake pipes and goose-necks to the ordinary collector main wherein the gases are cooled by spraying with ammonia liquor or ammonia liquor and tar to reduce the temperature of the gases and to separate tar constituents therefrom. The gases may be conveyed thereafter through the usual cross-over main to condensers in which further cooling is effected to separate tarry oils from the gases which may be treated thereafter in the usual manner for the recovery of light oils and ammonia. The tar and tarry oils which are separated in the manner described may be subjected to distillation in accordance with the present invention.

For the purpose of distilling the tar and oils one or more of the ovens of the battery may be connected to the electrical precipitator either through the usual uptake pipes or through separate uptake pipes provided for that purpose. If the usual uptake pipes supply the hot gases to the electrical precipitator, valved connections can be provided so that the gases may be diverted to the collector main when distillation is not carried out. Preferably the electrical precipitator is disposed at the rear of the ovens and is connected to one or more of the ovens through a separate uptake pipe or pipes while the ovens are also connected to the ordinary collector main and valves are provided to permit the delivery of the gases either to the collector main or to the electrical precipitator as may be desired.

The electrical precipitator may be of a type similar to the well known Cottrell precipitator and should be constructed so as to withstand the relatively high temperatures to which it is subjected in the operation as described. It, as well as the uptakes and collector main connected to it, may be insulated advantageously to prevent the loss of heat from the gases. This is particularly desirable if the recovery of the maximum quantity of heavy oils from the gases subsequent to cleaning thereof is desired.

The operation of an electrical precipitator consists in passing the gas to be treated between electrodes whose difference in electrical potential is very great. Experience has shown that it is best to use a high potential rectified alternating current. The alternating current (the primary) is sent through a step-up transformer to produce the high potential current (the secondary) which is then rectified to an intermittent uni-directional current, for example, by means of a rotary converter. The rectified current is delivered from the converter to the electrical precipitator at practically the potential at which it leaves the transformer.

The electrical precipitator consists essen-

tially of a group of vertical pipes with a wire or rod in the centre of each, the pipes being connected to proper headers for the introduction and discharge of the gases. The pipes generally constitute the positive electrodes and the wires or rods the negative electrodes. The size of the pipes may vary, but in general pipes of less than six inches in diameter are not employed. Electrical precipitators with pipes six inches in diameter using secondary voltages from 35,000 to 50,000 volts are satisfactory for the purpose of this invention. It is generally best to operate with maximum potential difference (secondary current) between electrodes, this maximum being just below the break-down voltage at which arcing occurs. It will be understood that the wires or rods are insulated from the tubes and casing.

The efficiency of the cleaning is dependent upon several variables. Satisfactory cleaning of the gas may be accomplished if the time of treatment is of the order of one second, although this time may be varied widely, depending upon the character of the oil to be removed from the gases after passing through the precipitator. In working with tubes six inches in diameter and nine feet long, for example, an oil substantially free from all tarry matter or free carbon has been obtained with a time of treatment of from one and one-half to two seconds, that is, a gas velocity through the tubes of from 6 to 4.5 feet per second. This gives an efficiency of cleaning of approximately ninety-nine per cent. If small amounts of tar are not objectionable in the oils recovered, the time of treatment may be limited, e. g. to 0.5 to one second, or a gas velocity of eighteen to nine feet per second may be employed, to obtain incomplete cleaning of the gases.

The electrical precipitator is provided with a chamber below the tubes which is separated therefrom preferably by a baffle. The hot gases from the uptake pipe or pipes are delivered directly to this chamber and pass therethrough in intimate contact with the tar or oil to be distilled which is introduced to the chamber, e. g. through a plurality of spray nozzles under sufficient pressure to ensure the sub-division of the tar or oil into fine particles which facilitate the distillation of the oil constituents. As hereinbefore indicated, oil or an aqueous cooling agent such as ammonia liquor can be introduced either with the tar or through separate spray nozzles or these cooling media can be delivered to the goose-necks and mingled with the hot gases before they enter the chamber at the bottom of the precipitator, where the gas temperature is too high or the tar supply is insufficient to utilize all the heat of the gases at a high temperature. By regulation of the amount of the cooling media supplied, the temperature of the gases can be regulated

at will and the distillation can be conducted, therefore, in a manner to permit the production of pitches and oils having the desired characteristics.

- 5 As a substitute for or adjunct to the spray nozzles through which the tar or oil to be distilled is introduced, the chamber at the bottom of the precipitator may contain means for mechanically atomizing or 10 spraying the tar or pitch into the gases, such as a cylinder which is adapted to be rotated at relatively high speed. This cylinder may dip slightly into a body of tar or oil in the bottom of the chamber and 15 may thus throw the tar or oil in the form of relatively small particles into the stream of gases flowing through the chamber to facilitate intimate contact between the tar or oil and the gases. The tar or oil is thus 20 thrown repeatedly into the stream of gases and is subjected to the heat thereof for the purpose of distilling the volatile constituents, leaving pitch which may be withdrawn either continuously or intermittently as a 25 product of the distillation. Other devices for causing intimate contact between the tar or pitch and the gases may be used.

The gases escaping from the electrical precipitator may be delivered to a suitable 30 condensing system in which they may be cooled in order to separate the desired condensable oils. These oils, which consist of a mixture of several constituents, may be recovered by total condensation in a single 35 fraction, or they may be fractionally condensed. The dew points of the gases for these several constituents are different and it is possible by fractional condensation to recover oils having varying characteristics, 40 such as a heavy creosote oil and a lighter tar acid or carbolic oil. Fractional condensation may be carried out in condensers designed to cool the gases in stages and to separate the condensed oils in fractions 45 therefrom. After such separation of the oil constituents the remaining gases may be delivered to the ordinary collector or cross-over main, in which case they mingle with the gases from the other ovens of the battery, or they may be conveyed to the ex- 50 hauster which maintains the pressure balance in the gas system and there mingle with the gases from the other ovens of the battery after the latter have been cooled to condense and remove tar and oil therefrom.

The invention can be utilized also by subjecting the tar to be distilled to distillation in successive steps with hot gases from the ovens followed by electrical precipitation of the gases. The gases from any desired number of ovens may be utilized in this manner. Preferably one, two or more ovens are connected to each successive distillation apparatus. The gases to be thus utilized can be 60 diverted from the ordinary uptake pipes by

the provision of suitable connections and valves, but preferably separate uptake pipes are provided, for example, at the rear of the ovens and these uptake pipes are connected to the distillation apparatus, valves being provided to permit diversion of the gases from the selected ovens from the usual collector main into the distillation apparatus. The distillation apparatus may vary in form. A suitable apparatus consists of a short collector main divided by diaphragms into separate distilling sections, each of which may be connected to one or more ovens. An electrical precipitator may be mounted above each of the distilling sections of the collector main and may be connected directly thereto so that the gases after intimate contact with the tar to be distilled pass immediately through the electrical precipitators for the purpose of separating entrained liquid and solid particles from the gases. The clean gases may then be conveyed separately to condensing systems wherein they are cooled to recover the condensable constituents. The diaphragms should extend from the top of the collector main toward the bottom thereof to the extent required to prevent mingling of the gases from the separate sections, that is to say, a seal should be provided by the tar and pitch flowing through the collector main at the bottom thereof. The tar and pitch may thus flow through the main, being subjected therein to successive distillation by the hot gases in the distillation sections of the main. The progressive distillation of the tar and pitch results in the separation of lighter and heavier oil constituents progressively and the production of a pitch having the desired characteristics which may be withdrawn from the end of the short collector main. The degree of hardness of the pitch thus produced can be modified by regulating the conditions of distillation. Pitch of intermediate melting point may of course be withdrawn from intermediate compartments.

The tar and pitch to be distilled may be introduced at one end of the collector main and may be intimately mingled with the hot gases, for example, by means of spray nozzles which divide the tar or pitch into relatively fine particles, or by means of mechanical spraying or atomizing devices. If spray nozzles are employed, the tar or pitch in the separate distillation sections can be withdrawn and recirculated through the spray nozzles by providing pumps and suitable connections for that purpose. Preferably, however, the mingling of the tar with the hot gases is effected by the provision in the separate sections of mechanical atomizers, e. g., cylinders rotated at high speed and adapted to dip into the bodies of tar and pitch in the bottom of each section and to throw the tar or pitch in the form of fine particles into the

70

115

120

125

130

hot gases introduced to the respective sections. Thus, the tar or pitch in each section is subjected repeatedly to intimate contact with the hot gases to effect the further 5 distillation of the tar or pitch. The distillation is also improved by contact of the hot gases with the liquid constituents which are returned constantly from each of the electrical precipitators as the result of the separation 10 of such constituents from the gases therein. Other forms of agitating devices adapted to accomplish the purpose of the invention may be used in place of or as adjuncts to either the spray nozzles or the rotating cylinders. 15

The electrical precipitators may be of the type hereinbefore described. A number of such precipitators may be used and the number of sections in the short collector main 20 may be similarly multiplied so as to provide for any number of successive distillations of the tar and pitch by contact with the hot gases from the ovens. Each distillation section of the collector main may be connected to 25 any number of ovens to secure the necessary supply of hot gases for distillation of the tar and pitch. In place of the short collector main divided by diaphragms into separate distillation sections, independent receptacles 30 can be utilized and the tar and pitch can be directed in succession into such receptacles, it being understood that each receptacle will be connected to an electrical precipitator and that provision will be made for the intimate 35 contact of the tar and pitch to be distilled with the requisite amount of hot gases, either by the use of spray nozzles with means for recirculating the tar or pitch therethrough or by the provision of suitable mechanical agi- 40 tating devices in each receptacle.

The gases, after cleaning in the electrical precipitators, may be cooled and the oil vapors condensed in a single condenser, but preferably separate condensers will be provided 45 to permit the recovery of the lighter and heavier oil constituents which are removed from the tar and pitch by the successive distillations. After condensation of the condensable constituents the gases can be delivered either to the ordinary collector or cross-over main where they mingle with the gases from the remaining ovens of the battery or they can be delivered to and mingled with the gases from the remaining ovens after the latter have passed through the ordinary condensing system. 55

The tar or oil which is distilled according to the present invention may be tar or oil produced at the same coke-oven plant or at another plant. The tar may be a heavy tar, light tar or heavy or light tar constituents which it is desired to distill for the purpose of separating distillate oils therefrom. Tar from other sources, such as gas-house tar, 60 vertical retort tar, or water-gas tar, etc., may

also be distilled. Where blended or composite pitches are desired or composite or blended distillates, two or more different kinds of tar can be mixed in suitable proportions and distilled together, giving directly a composite pitch product. For example, horizontal gas-retort tar with high free carbon content can be admixed with coke-oven tar and the mixture can be distilled to give a composite pitch higher in free carbon than the pitch from the coke-oven tar alone and to give a composite oil distillate. The invention may be utilized likewise to distill oils and particularly dirty or contaminated oils for the purpose of recovering clean oils and pitch residues therefrom. Such oils can also be utilized for the purpose of regulating the temperature of distillation in the manner hereinbefore described. 70 75 80 85

The present invention is of more or less general application to the distillation of tar and oils and the recovery of distillates. The invention involves utilization of the hot coke-oven gases for the distillation of tar or oil by bringing the tar or oil into direct and regulated contact therewith in the bottom of the electrical precipitator and then immediately cleaning the gases by electrical precipitation to separate solid and liquid particles therefrom before the gases are finally cooled to effect the condensation of the vapors of the desired oils carried therein. The invention will be further illustrated by the following more detailed description in connection with the accompanying drawings showing apparatus embodying the invention and adapted for the practice thereof. In the drawings, 90 95 100 105

Fig. 1 is a plan view of a portion of the coke oven illustrating the application of the invention thereto;

Fig. 2 is a vertical section through the electrical precipitator;

Fig. 2A is another section through the precipitator;

Figs. 3 and 3A are similar views illustrating the application of the rotating cylinder therein;

Fig. 4 is a plan view of a portion of a coke-oven battery illustrating the application of successive distillation of the tar and pitch; and

Fig. 5 is an enlarged vertical section of a short collector main having separate distillation sections with electrical precipitators connected thereto. 110 115 120

Referring to the drawings, 5 indicates a battery of coke ovens having individual uptake-pipes and goose-necks 6 which connect the ovens with a collector main 7. The latter may be of any usual form and construction and is designed to receive all of the gases from the individual coke ovens and to deliver them through a centre box 8 to a cross- 125 130

over main 9 which is connected to the condensing apparatus hereinafter described. The collector main may be provided with a plurality of spray nozzles 10 designed to 5 distribute ammonia liquor or ammonia liquor and tar to the gases flowing through the collector main for the purpose of reducing the temperature of these gases and of flushing the collector main. The ammonia 10 liquor may be delivered to the spray nozzles through pipes 11 and 12 connected thereto and to a source of supply such as a tank 13, a pump 14 being provided to permit the introduction of the ammonia liquor or ammonia 15 liquor and tar to the collector main under a suitable pressure. The cooling liquid may be supplied likewise to the goose-necks leading to the collector main through spray nozzles 15 which are supplied by the 20 pipe 12.

The cross-over main 9 conveys the partially cooled gases to condensers 16 wherein they are further cooled to separate tarry oils therefrom. The tar and oils which separate 25 in the cross-over main and in the condensers may be withdrawn through pipes 17 and 18 and delivered to decanters 19 and 20 wherein the ammonia liquor is separated from the tar and tarry oils. The tar and 30 tarry oils may be delivered through pipes 21 to a storage receptacle 22 to be withdrawn as hereinafter described and subjected to the heating effect of hot coke-oven gases for the purpose of distilling the tar and tarry oil. 35 Tar from 19 and tarry oils from 20 may if desired be kept separate by providing storage 22'. The gases from the condensers 16 are drawn through an exhaust 23 and are delivered thence to the usual apparatus for 40 the recovery of ammonia and light oils, etc.

The apparatus as hereinbefore described is that commonly employed in by-product recovery systems in connection with coke ovens, and it will be understood that such apparatus 45 may be operated in the usual manner for the purpose of cooling and condensing the tar and tarry oil constituents of the gases. The application of the present invention does not, therefore, involve any considerable modification of the ordinary coke-oven plant.

In carrying out the invention the electrical precipitator or precipitators employed for distillation of the tar may be disposed conveniently 55 at the rear of the ovens. Each precipitator may be connected to a single oven or to a plurality of ovens. Valves may be provided to divert the hot coke-oven gases from the selected ovens into the precipitators, 60 the connections between these ovens and the ordinary collector main being at the same time closed.

Each precipitator may consist of a shell 24 enclosing a number of tubes 25 supported in 65 heads 26 and 27 within the shell. A cham-

ber 28 is provided at the lower end of the shell, and may be partially separated from the tubes by a baffle 29, although the baffle is in many cases not required. The hot gases may be delivered to this chamber through an uptake pipe and goose-neck 30, for example. An outlet 31 permits the escape of the gases from the precipitator after the latter have passed through the tubes.

A plurality of electrodes 32 preferably in the form of metal rods extend through the tubes and are supported from a bus-bar 33 located near the upper end of the tubes. The bus-bar 33 extends at both ends into casings 34 which enclose insulators 35 upon which the bus-bar is supported. The high tension current line extends into one of the casings and connects with the bus-bar, thus supplying the necessary current from any suitable source of uni-directional current under high tension. The casing of the separator is grounded or otherwise connected to the source of current to complete the circuit. The casing and tubes form the positive electrode, the electrodes connected to the bus-bar being negative. The form and arrangement of the conductors in the circuit can be varied. The arrangement should be such as to supply high tension uni-directional current to the electrodes, thereby permitting continuous silent discharge between the electrodes and the tubes through which the gases pass.

The tar or oil to be distilled is introduced to the chamber at the bottom of the precipitator through a plurality of spray nozzles 36 which are supplied through a pipe 37 and pump 38 from any suitable supply of tar or oil to be distilled. Oil or ammonia liquor or other aqueous cooling agent can, when desired, be introduced similarly for the purpose of regulating the temperature of the gases. The gases may be precooled by the introduction of oil or ammonia liquor through spray nozzles 39 supplied through a pipe 40 from any suitable source thereof.

In order to obtain maximum distillation at a high temperature, the uptake pipes and precipitator can be best insulated by providing heavy insulation, or heating jackets, to prevent cooling of the gases from the ovens or retorts, so that the gases will pass through the precipitator at a high temperature, and so that effective distillation at a high temperature can be obtained.

The tar or oil to be distilled is introduced to the hot gases in finely divided form and, being mingled intimately with the gases, is subjected to the heat thereof so that the desired volatile constituents are separated in the form of vapor. The gases carrying the vapor and some of the tar in the form of globules or "tar fog", together with solid materials such as carbon, etc., in finely divided form, enter the tubes of the electrical precipitator and pass therethrough, being subjected

to the electrical discharge which through ionization of the solid and liquid particles causes them to separate from the gases and accompanying condensable vapors. The separated liquids, together with the solid particles, run down the inner walls of the tubes and are returned for further contact with the hot gases to the chamber at the bottom of the precipitator. Owing to the fact that the pitch in finely divided form which enters the tubes of the precipitator is liquid at the temperature of treatment, the latter are thoroughly flushed with relatively liquid constituents and accumulation of solid pitch thereon is avoided. This is the case with pitches produced from coke oven tar up to about 300-325° F. melting point. At higher gas temperatures, with corresponding higher melting point pitches, accumulations of pitchy material may form on the surfaces of the electrical precipitator tubes. The melting point range mentioned is not to be regarded as narrowly limiting, since conditions at different plants and with different tars will cause variations in the maximum permissible temperatures at each. The pitch which is produced by the distillation can be withdrawn through an outlet 41 at the bottom of the precipitator and delivered through a pipe 42 to a pitch receptacle 43 from which it may be taken as required for any desired use. All or a portion of the pitch can be recirculated through a pump 44 and pipe 45 to the spray nozzles so that it will be again atomized and subjected to the heat of the hot coke-oven gases for further distillation and separation of vaporizable constituents therefrom, or the pitch may be recirculated directly from the bottom of the precipitator and the required amount may be continuously withdrawn to 43.

The gases carrying the condensable vapors escape through an outlet 46 and are delivered through a pipe 47 to the condensing system. This may comprise a plurality of fractional condensers 48 in which the gases are cooled in stages to separate the desired condensable oils in fractions. The oils thus separated may be delivered through pipes 49 to receptacles 50 therefor. The gases, after cooling, may be conveyed by exhauster 51' through a pipe 51 to the collector main or through a pipe 52 to the exhauster 23. In either case the gases freed from the condensable constituents are mingled with the gases derived from other ovens of the battery and are subsequently subjected to further treatment for the recovery of light oils, ammonia, etc.

In place of or as an adjunct to the spray nozzles, the electrical precipitator may be provided as indicated in Fig. 3 with mechanical spraying devices such as a cylinder 53 so disposed within the chamber at the bottom of the precipitator as to dip slightly into the tar or oil therein. The cylinder is adapted to

be rotated at a relatively high rate so that the tar or oil in the bottom of the chamber will be thrown into the stream of gases in a finely divided condition and thus mingled therewith for the purpose of facilitating the distillation and separation of the oil constituents. The cylinder may rotate, for example, at 900 revolutions per minute and when so operated will thoroughly atomize the tar or oil, returning portions thereof for further contact with the hot coke-oven gases to ensure thorough and effective distillation.

Referring to Figs. 4 and 5 of the drawings, the ovens of a coke-oven battery 55 may be connected by the usual uptake pipes and goose-necks 56 to a collector main 57 in which the gases may be cooled in the usual manner by the application of sprays of ammonia liquor or ammonia liquor and tar. The gases pass through a cross-over main 58 to condensers 59 wherein they are further cooled to separate tarry oil constituents. The tar which separates in the collector main 57 and cross-over main 58 may be withdrawn through a pipe 60 and delivered to a decanter 61 in which the ammonia liquor is separated therefrom. The tarry oils which separate in the condensers 59 are delivered through a pipe 62 to a decanter 63 for the separation of ammonia liquor therefrom. The ammonia liquor passes through pipes 64 to a storage tank 65 from which it may be returned to a pipe 66 and pump 67 for further use in the collector main. The tar from the decanters 61 and 63 may be delivered to a storage tank 68 by pipes 69 or may be kept separate by providing tank 68'. The gases from the condensers 59 are withdrawn through a pipe 70 by an exhauster 71 which maintains the pressure balance in the system. The gases may be treated subsequently in apparatus (not shown) for the recovery of ammonia and light oils in accordance with the usual practice.

To permit operation in the manner hereinbefore described a short collector main 72 may be provided preferably at the rear of the ovens and divided by diaphragms 73 into a plurality of distillation sections, each of which communicates directly with an electrical precipitator 74 of the type hereinbefore described. Each of the distillation sections of the collector main is connected to one or more ovens of the battery through uptake pipes and goose-necks 75 so that hot gases from the ovens may be delivered directly to the separate sections. The usual valves will be provided to prevent discharge of the hot gases from the selected ovens to the collector main 57 while distillation is in progress.

The tar or tarry oil to be distilled is introduced at one end of the collector main 72 by a pipe 76 from the storage tank 68 or 68'. Tar or oil from any other source such as a storage tank 77 may be introduced similarly

to the collector main, a pump 78 being provided to permit the introduction of the materials under pressure when required. The tar or pitch flows through the collector main 5 past the diaphragms 73 which divide the collector main into separate distillation sections, and the resulting pitch is withdrawn through a pipe 79 and is delivered to a suitable storage receptacle 80. In each of the 10 distillation sections the material being distilled is intimately mingled with the hot gases, for example, by a cylinder 81 rotating therein at high speed and dipping slightly into the body of material in the bottom of the 15 collector main. More than one such cylinder may be employed in each section if desired. Thus, in each section of the collector main the liquid material therein is subjected repeatedly to intimate contact with the hot gases entering the respective sections and the desired 20 vaporizable constituents of the tar are thus separated therefrom and are carried with the gases into the electrical precipitators 74.

In the electrical precipitators the gases are 25 subjected to the electrical discharge which effects the separation of the solid and liquid particles in the gases, leaving the latter free from tarry constituents. The liquid and solid particles drain backwardly from the tubes 30 of the precipitator into the respective distillation sections of the collector main. The precipitators will be operated at temperatures adapted to retain the desired oil constituents in the gases.

35 The clean gases are withdrawn through pipes 82 and are delivered to condensers 83 wherein they are cooled to recover the desired oils therefrom. The oils are withdrawn and are delivered to storage receptacles 84. 40 Under proper conditions of operation these oils will vary in character as the result of the successive distillations of the tar and pitch in the collector main. The gases from the condensers are delivered through pipes 85 and 86 and may be returned to the collector main 57 through exhauster 89 and pipe 87 or through a pipe 88 to the exhauster 71.

As in the preceding embodiment of the invention, the conditions of temperature in the 50 collector main and the connected precipitators may be regulated by the addition of oils or ammonia liquor with the tar to be distilled either separately or by mingling the oil or ammonia liquor with the tar before 55 distillation, where a temperature lower than maximum is desired. The invention can be utilized for the distillation of dirty oils either with or without the addition of tar thereto for the purpose of recovering clean oils and 60 particularly oils having different characteristics and being adapted therefore for different uses.

In some cases a limited distillation only 65 of the tar is desired, and this can readily be obtained by using a limited amount of hotflow of

gas at a high temperature, avoiding preliminary cooling of the gas, or by using a larger amount of gas at a lower temperature, or by limiting its distillation by the use of ammonia liquor or added oil in regulated amounts. 70

In other cases, however, it is desirable to secure the maximum oil yield from the tar and the production of high melting point pitch as a residue. This can readily be accomplished by insulating the uptake pipes, 75 distillation main and precipitator, so as to use the gases at practically their maximum temperature for the distillation and by regulating the supply of tar and the intimacy of spraying to obtain the desired distillation. Pitches of, e. g., 400° F. melting point 80 or higher and oil yields around 75 to 80% or higher are thus obtainable from coke oven tar.

The apparatus as described permits the distillation of tar and oils and the utilization for this purpose of a portion of the heat in the coke-oven gases, or of the heat of a portion of the gases. It likewise permits the separation of tarry constituents and solid materials from the hot gases and, when the operation is properly regulated, the gases passing to the condensers are cleaned and the oils separated therein are likewise clean and free from tarry constituents. 85

90 The advantages of the invention have been set forth and the preferred embodiments have been described. It is to be understood, however, that various changes may be made in the form and arrangement of the apparatus and in the operation as described without departing from the invention or sacrificing any of the advantages thereof. 95

100 While the invention is described more particularly as applied to coke oven operation, it is of broader application, and applicable, for example, to gas retort plants for the distillation of tar by the gas retort gases. By insulating the uptake pipes or standpipes to 105 reduce heat losses, effective distillation can be obtained with gases at a high temperature, while without such insulation, and with considerable atmospheric cooling of the gases, the distillation will take place with gases of lower temperature. 110

I claim:

115 1. The method of distilling tar and cleaning the resulting gases and vapors which comprises spraying tar into hot gases thereby distilling volatile constituents from the tar and loading the gases with finely divided particles of tar, immediately subjecting the resulting gases and vapors containing such finely divided particles of tar in suspension to an electrical discharge in an electrical precipitator whereby suspended liquid particles are precipitated onto the walls of the precipitator, and so regulating the distribution of tar 120 in the gases that a continuous and voluminous 125 precipitated liquid is produced on the 130

walls of the precipitator thereby flushing the walls and preventing accumulation of solid tar or pitch thereon.

2. The method of distilling tar and cleaning the resulting gases and vapors, which comprises spraying the tar into a stream of hot gases thereby distilling volatile constituents from the tar and loading the gases with finely divided particles of tar, immediately 10 passing the resulting gases and vapors containing such finely divided particles of tar in suspension in an upward direction directly into and through an electrical precipitator located above the zone of distillation and subjecting the gases and vapors to an electrical 15 discharge therein whereby suspended liquid particles are precipitated onto the walls of the precipitator, so regulating the distribution of tar in the gases that a continuous and voluminous flow of precipitated liquid is produced 20 on the walls of the precipitator thereby flushing the walls and preventing accumulation of solid tar or pitch on the walls, returning the precipitated matter directly to the still, 25 blending it with tar therein, and continuing the distillation of the tar until it is distilled to pitch of the desired melting point.

3. In the operation of a coal distillation plant involving a tar still wherein tar is distilled in contact with hot coal distillation gases, and an electrical precipitator wherein solid and liquid particles are removed from the gases and vapors resulting from such distillation, the method which comprises loading 35 the hot gases with finely divided particles of the tar, immediately thereafter, while the gases are still at a high temperature and yet contain a large proportion of tar particles, subjecting the gases to electrical precipitation 40 to precipitate residual liquid particles, the distribution of the tar in the gases being so regulated with regard to the volume and temperature of the gases that a continuous and voluminous flow of the precipitated liquid is 45 produced on the walls of the electrical precipitator thereby flushing the walls and preventing the accumulation of solid tar or pitch thereon.

In testimony whereof I affix my signature.
50 STUART PARMELEE MILLER.
